UNITED STATES PATENT OFFICE.

THOMAS FLETCHER, OF WARRINGTON, COUNTY OF LANCASTER, ENGLAND.

GAS-BURNERS FOR HEATING PURPOSES.

SPECIFICATION forming part of Letters Patent No. 291,475, dated January 1, 1884.

Application filed July 11, 1883. (No model.) Patented in England April 28, 1882, No. 2,019, and in Canada December 7, 1882, No. 15,019.

To all whom it may concern:

Be it known that I, THOMAS FLETCHER, a subject of the Queen of Great Britain, residing in Warrington, in the county of Lancaster and Kingdom of Great Britain, have invented certain new and useful Improvements in Gas-Burners for Heating Purposes, of which the following is a specification.

This invention relates to gas-burners for heating purposes, and has for its object the production of a large flame-surface in a comparatively small area without the use of metallic gauze, and without any danger of the flame lighting back through the body of the burner to the gas-jet.

The invention also relates to certain details of construction, all of which will be fully and clearly hereinafter shown and described by reference to the accompanying drawings, 20 in which—

Figure 1 is a plan or top view; Fig. 2, a side elevation, and Fig. 3 represents a vertical longitudinal section through line X X, Fig. 1.

25 The burner *a* is made of cast-iron, and formed of one piece, consisting of the following-named parts: first, the inlet-tube *a'*, having the air-opening *a²*; second, the center burner, *a³*, provided with a series of narrow 30 parallel slits, *a⁴*; third, the circular or annular burner *a⁵*, surrounding the burner *a³*, and provided with a series of radially-arranged narrow slits *b*.

B' represents the gas-burner or nozzle. It 35 is made to screw into the burner *a*, so that the opening *b²* will be in a line with the top of the opening *a²*, or a little above it. The burner *a* is secured to a frame, *b³*, by means of the screws *b⁴*. This supporting-frame *b³* is also 40 made of cast-iron or other suitable material, cast in one piece, and consists of the legs *b⁵* *b⁶*, supporting rim *c*, part *c'*, having the leg *b⁶*, and upper vertical supports, *c'*, for holding or supporting the articles to be heated or for 45 other purposes. The maximum width of the slits *a⁴* and *b* should not exceed one-fifteenth of an inch, and they must be formed by cutting or some equivalent process, so as to in-

sure an approximate parallelism of the two faces of the slits. If they are all cast through 50 or nearly through the body of the burner and then opened, as is frequently the practice, the result is not satisfactory, as when the mixture of gas and air supplied to the burner is highly explosive the flame is very liable to 55 fly back to the internal part of the burner. The width of slit which I find most satisfactory is one-thirtieth of an inch, and any departure from this either way gives in practice a less satisfactory result. With the slit one-thirtieth 60 of an inch in width cut through the metal of about one-eighth of an inch thick, the most explosive mixtures of gas and air can be easily and perfectly burned. Although I adopt these sizes generally, I do not limit myself to 65 them. The tube or center burner and annular burner are in open communication with a supply or inlet tube, *a'*.

The air-inlet *a²* is at the end of the supply-tube farthest from the burner, and is provided 70 with the gas jet or burner *B'*, which may be of the usual or any special form of construction. In gas-burners made according to these improvements atmospheric air is combined with the gas in due proportion in the supply-tube, the proportions being regulated by 75 the size of the gas-inlet. From the supply-tube *a'* the mixture of gas and air passes through the slits over which combustion takes place. The employment of these slits, instead of holes or slots hitherto employed, 80 compels the combined gas and air to issue from the burner in a series of parallel or approximately parallel thin films. By this mixture the air has free and immediate access to a greater surface of the inflammable 85 mixture at the point of emergence, and the result is a flame possessing a more intense heating-power. Moreover, I am enabled thereby to obtain a powerful burner of small 90 dimensions.

I claim—

1. A gas-burner for heating purposes, consisting of the inlet or supply tube *a'*, having an air-opening, *a²*, and gas-jet *B'*, and a center burner, *a³*, arranged within an annular 95

burner, a^5 , each being provided with a series of narrow cut openings or slits, a^4 and b , the whole mounted upon a suitable supporting-frame, substantially as specified.

5 2. A gas-heating burner consisting of the following parts, all cast or formed of one piece: the inlet or supply tube a' , provided with the air-opening a^2 , gas-jet B' , and an an-

nular burner, a^5 , surrounding the burner a^3 , substantially as described.

THOS. FLETCHER.
